UNITED STATES PATENT OFFICE

90,991

DESIGN FOR A SERVING TRAY OR SIMILAR ARTICLE

Clarence P. Meier, Forest Hills, N. Y., assignor to
The American Art Works, Inc., Coshocton, Ohio, a corporation of Ohio

Application July 24, 1933. Serial No. 48,816

Term of patent 3½ years

To all whom it may concern:

Be it known that I, CLARENCE P. MEIER, a citizen of the United States, residing at Forest Hills, in the county of Queens and State of New York, have invented a new, original, and ornamental Design for a Serving Tray or Similar Article, of which the following is a specification, reference being had to the accompanying drawing forming part hereof.

Fig. 1 is a perspective view of the serving tray, showing my new design.

Fig. 2 is a side view.

I claim:

The ornamental design for a serving tray or similar article, substantially as shown.

CLARENCE P. MEIER.
